UNITED STATES PATENT OFFICE.

HENRI CHAUMAT, OF PARIS, FRANCE.

INDIGO-DYEING VAT.

981,380.

Specification of Letters Patent. Patented Jan. 10, 1911.

Application filed August 19, 1908. Serial No. 449,247.

To all whom it may concern:

Be it known that I, HENRI CHAUMAT, a citizen of the Republic of France, and resident of Paris, France, have invented new 5 and useful Improvements in Indigo-Dyeing Vats, which improvements are fully set forth in the following specification.

This invention relates to a special vat for dyeing by means of indigo, wool previously 10 freed from grease, or any other textile material, raw or spun, and even fabrics.

This special vat has been invented for the practical application of the process of preparation of indigo baths by the well known 15 electrolytic method, fully described in U. S. Patent No. 885,978, issued April 18, 1908. By means of the said electrolytic process highly concentrated solutions of white indigo may be quickly prepared. For many 20 reasons, more particularly owing to the cost, it is advisable to separate the preparation of the said solutions, and the dyeing proper. The dyeing is effected in a special vat as hereinafter described, and the preparation 25 of highly concentrated solutions of white indigo in separate electrolytic vats. The solutions of white indigo obtained, are mixed, when it is desired to use them either with hot boiling water alone or with hot 30 water to which a suitable quantity of sulfites, bisulfites or sulfids of alkalies or of alkaline earths has been added, so as to deprive the said water of all the oxygen in solution therein. The liquid obtained by 35 the mixture is used direct for supplying the dyeing vats.

The dyeing vat comprises a cylindrical metal receptacle closed at the top by a cover which can be folded down and closed 40 in an air-tight manner. Within the said vat are superposed perforated baskets in which are placed the wool or other materials to be dyed. A vacuum is produced in the said receptacle, and a dilute solution of white 45 indigo as previously mentioned, is introduced through a suction pipe. The impregnation of textile fibers with the solution of white indigo is thus effected in a vacuum. This results in a greatly improved impregnation. After being left in contact a sufficient length of time, the vat is placed in communication with the atmosphere and opened, the baskets are withdrawn, and the 50 wool or other dyed materials are submitted 55 to the ordinary finishing or oxidizing operation.

In addition to the improved impregnation of the fabrics with the solution of white indigo, dyeing in a vacuum offers special advantages, more particularly from the point 60 of view of the application of the electrolytic process forming the subject of the above identified patent. This advantage will appear from the following considerations. In all indigo vats at present used, 65 in which dyeing is carried out in the open air, whether they be fermentation vats or the so-called chemical vats (in which use of hydro-sulfites or other products is made), an excess of reducing agent (special bacteria or chemical products) is contained in 70 the bath. The introduction of the wool into the bath, which necessarily carries into the liquid a great quantity of air, or simply the action of the air on the surface, produces 75 an oxidation of the white indigo of the bath causing it to become insoluble blue indigo. The said blue indigo in suspension in the bath is not fixed by the wool, and has to be reduced again. It is therefore necessary to 80 work fermentation vats slowly, so as to leave the ferment sufficient time to reduce the blue indigo again, so that it is impossible to effect a great number of operations in one day. In chemical vats, in order to avoid oxidation, it is necessary to employ the reducing 85 agent in excess and to add the same during the treatment, which is an expensive matter. In the electrolytic process already referred to, a pure solution of white indigo containing no reducing agent is used. Consequently all the blue indigo placed in suspension in an insoluble state in the bath by the oxidizing action of the air, must be 90 collected in order to be again reduced in electrolytic vats. The blue indigo is not a lost product, but it will be seen that dyeing 95 in a vacuum, will result in practically avoiding any oxidation of the indigo of the bath by the air, and therefore in doing away with repeated reduction and with the additional cost of labor and expenditure of electric energy for carrying on the operation. From another point of view, the following 100 may also be added: The utilization of pure and concentrated solutions of white indigo, absolutely without any deposit, permits, on the one hand to a considerable extent, the reduction of the volume of the dyeing liquid, which considerably reduces the heating 105 expenses, and on the other hand enables the liquids to be used in a sufficiently concen- 110

trated state for reducing the number of operations to one or two even for the darkest color.

An example embodying the invention is shown in the accompanying drawings, in which—

Figure 1 is a vertical sectional view of the vat, Fig. 2 shows a portion of a horizontal section through the vat and water-gage, Fig. 3 is a horizontal sectional view taken substantially midway of the vat, Fig. 4 is a partial vertical sectional view of the baskets, and Fig. 5 shows a horizontal section of a basket.

15 The vat comprises a body-portion D formed of double partitions a a' of steel plate reinforced by iron uprights a^2 of I-shaped cross-section arranged around the circumference. This body D is closed at the 20 top by a cover A hinged by means of a pin O and counterbalanced by a weight B, as shown. The lever-arm A' is provided with a groove to guide a chain-supporting weight B, the profile of said lever-arm being so de 25 signed that the cover is practically balanced for all positions.

The top of the vat on which is placed the cover A comprises a cast-iron cylindrical portion C carrying the tube R leading to the 30 vacuum, the water-gage Q, the ears e and the pin O. The vacuum-tube R is closed by a three-way valve, not shown. This tube R serves both for exhausting the air from the vat and also for permitting the air to re-enter at the end of the operation. A bronze tube I fixed in the cover A carries a thermometer J. The bottom E of the vat also of cast-iron is furnished with two feet e', e' by which the vat is supported. Three tubes 35 enter the vat through the bottom E, the tube P for solution of white indigo, the tube N for the introduction of any special liquids which may be needed, and tube M for introducing steam. The tube P serves also for 40 the removal of the liquid at the end of the operation, and for this purpose is supplied with a three-way cock (not shown). The bottom E is provided also with a central bearing-bore e² passing therethrough for the 45 reception of a spindle g² carrying a conveyer-screw G. The bottom E is provided also with a manhole (not shown). The bottom E is also provided with inwardly projecting lugs b for supporting the baskets. 50 The conveyer-screw G stands coaxial with the vat and is rotated by means of the wheel F suitably driven below the vat, and by its rotation causes a constant upward flow of the liquid in the central tube of the baskets, 55 thus assuring a continuous circulation of the liquids through the wool. The said central tube is surmounted by a sheet-metal cone K which acts to turn the liquids rising in the tube back upon the wool in the baskets. The 60

cone K has a sheet-metal base provided with 65 perforations, as shown, the perforations preferably increasing in diameter as they are more remote from the center of the base, whereby an even distribution of the flow of the liquids downward is assured.

70 Next to the wall of the vat is provided a coil II in communication with the pipe M for the purpose of circulating steam to raise the liquid in the vat to the required temperature.

75 The baskets L, L', L'' containing the wool have a bottom and top and lateral walls consisting of concentric cylinders, all formed of metal gratings, and the wool is placed in the space between the two cylinders. The baskets are hooked to each other, as shown in Fig. 4, in order that they may all be lifted out of the vat together. Thus the baskets remain superposed, coaxial with the vat, the cylindrical space being occupied by the screw 80 and the tube extending to the screw.

Having thus described my invention, I claim as new and desire to secure by Letters Patent:

1. In combination, a cylindrical vessel 90 having a lid at the top, a heating coil arranged next to the cylindrical wall of the vessel, a circulating screw at the axis of the vessel, baskets composed of an outer cylindrical wall and an inner cylindrical wall 95 and adapted to occupy the space between said screw and said coil, and means for exhausting air from said vessel.

2. In combination, a cylindrical vessel 100 having a lid at the top, a heating coil arranged next to the cylindrical wall of the vessel, a circulating screw at the axis of the vessel, baskets composed of an outer cylindrical wall and an inner cylindrical wall 105 and adapted to occupy the space between said screw and said coil, means for introducing a liquid into the vessel, and means for holding said baskets together and means for exhausting air from the vessel.

3. In combination, a cylindrical vessel 110 having an open upper end, a counterbalanced lid for the open end, a helical heating coil arranged next to the cylindrical wall of the vessel, a rotatable screw at the axis of the vessel, a series of superposed perforated baskets comprising inner and outer concentric walls and occupying the space between the coil and the screw, means for detachably holding said baskets in superposed position, and means for exhausting 120 air from the vessel.

4. In combination, a cylindrical vessel having an open upper end, a counterbalanced lid for the open end, a helical heating coil arranged next to the cylindrical wall of 125 the vessel, a rotatable screw at the axis of the vessel, a series of superposed perforated baskets comprising inner and outer concentric

tric walls and occupying the space between the coil and the screw, means for detachably holding said baskets in superposed position, a deflecting cone at the top of said screw, 5 means for introducing liquids into the vessel, strengthening ribs on the outside of the vessel and means for exhausting air from the vessel.

In testimony whereof I have signed this specification in the presence of two subscribers. 10
ing witnesses.
